(57) **CLAIM**

The ornamental design for a knife blade, as shown and described.

DESCRIPTION

FIG. 1 is a front, right-side perspective view of a knife blade in accordance with my design;

FIG. 2 is a rear, right-side perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines having consistent dash lengths (dash-dash-dash) represent portions of the knife blade that form no part of the claimed design.

The broken lines having variable dash lengths (long dash-short dash-long dash) in FIGS. 1-6 represent boundaries of the claimed design.
